PATENTED JULY 21, 1903.

A. DELGRANDE.

TOY GUN.

APPLICATION FILED JAN. 30, 1903.

NO MODEL.

Fig. 1.

UNITED STATES PATENT OFFICE.

ANTONIO DELGRANDE, OF JERSEY CITY, NEW JERSEY.

TOY GUN.

SPECIFICATION forming part of Letters Patent No. 733,946, dated July 21, 1903.

Application filed January 30, 1903. Serial No. 141,194. (No model.)

To all whom it may concern:

Be it known that I, ANTONIO DELGRANDE, a citizen of the United States, residing at Jersey City, in the county of Hudson and State of New Jersey, have invented a new and useful Toy Gun, of which the following is a specification.

My invention relates to toy guns; and the objects had in view in the invention are to combine in a toy gun of simple design which may be cheaply manufactured, means for detonating suitably-prepared explosive charges, means for firing from the gun by means of explosive charges the projectiles hereinafter described, and also means for discharging projectiles from the gun without the aid of any explosives. These objects are all attained in the construction hereinafter described, and shown in the accompanying drawings, in which—

Figure 1 is a side elevation showing in dotted lines the partial and complete detachment of the barrel from the gun. Fig. 2 is a vertical longitudinal section, on larger scale than Fig. 1, of the working parts of the gun. Fig. 3 is a transverse section on line 3 3 of Fig. 2. Fig. 4 is a section on line 4 4 of Fig. 2. Fig. 5 shows in perspective the actual size of the pyrotechnic projectile. Fig. 6 shows in perspective the actual size of an explosive charge of preferred form.

In all the figures corresponding parts are indicated by the same characters of reference throughout.

Referring to the drawings, my improved toy gun consists of a stock 1, having a forward extension 2, adapted to form a support for mechanisms hereinafter to be described and being provided with a spring-controlled trigger 3 and a trigger-guard 4 of the usual form. The extension 2 is pierced from top to bottom throughout a considerable portion of its length by a slot 5, whose forward end terminates in a vertical wall, as shown, and whose rearward end is formed by a sloping surface 6, extending from a point below a few inches in advance of the trigger-guard to the catch of the trigger itself above. Mounted on the forward extension 2 is the short barrel 7, pierced at its rearward end by a touch-hole 8, which communicates with the internal bore 9 of the barrel and has formed near

its rear end an internal shoulder 10, which is adapted to form a seat for an explosive charge, which will presently be described. The barrel 7 rests upon a base-plate 11, preferably cast integral with the barrel and having lugs 12 12, adapted to engage with the slot 5, and lateral projections 13 13, adapted to rest upon the upper surface of the extension 2, upon which the barrel is supported. The barrel 7 is connected with the stock by means of a frame 14, formed, preferably, of a single piece of wire of proper size, which is pivotally mounted in an opening 15, which pierces the stock just over the forward portion of the trigger-guard 4 and which is preferably provided with a bushing 16 to prevent wear. The frame 14 is also pivotally connected with the barrel 7, which has provided in the metal between the bore 9 and the base 11 an opening 17, in which the frame 14 is journaled. The distance of the barrel from the trigger is of course determined by the length of the frame 14, which also serves, together with a latch 18, which is passed through a hole 19 in the extension 2 and a hole 20, provided in the rearward lug 12 on the base supporting the barrel and adapted to register with the opening 19, to secure the barrel 7 in firm engagement with the extension 2. The latch 18 is removable from the holes 19 and 20, and when it is so removed the barrel may be swung backward on the frame 14, as shown in Fig. 1, or if it is desired to entirely remove the barrel from the gun the ends of the frame 14 may be sprung out of the opening 15 in the stock and the frame and barrel entirely separated from the rest of the gun structure.

In addition to the barrel 7 the extension 2 supports a plunger 21, which is adapted to reciprocate thereon and serves as means for detonating the explosive charges when seated in the touch-hole 8. The plunger 21 is preferably constructed, for the most part, of a cylindrical wooden block 22, provided at its forward end with a metallic cap 23, which is beveled on the lower portion of the forward end to cause it to slide readily upward over the base-plate 11, upon which the barrel is supported. The block 22 is pierced vertically by holes 24 25, through which is passed an elastic cord 26, preferably of rubber, and having a protecting-cover, of some textile material.

The elastic cord 26 extends from the under surface of the forward end of the extension 2, where it is secured by suitable means, upward through the slot 5 and the opening 24, downward through the opening 25 and the slot 5, to be secured on the under surface of the rear portion of the extension 2. The block 22 is notched on its under surface at 27 to provide means for engagement with the catch of the trigger 3, and a metallic protecting-piece 28 of any suitable form is provided to prevent the wearing of the block by the trigger. In order to cause the block 22 to slide more readily over the trigger, it is beveled on its under surface at the rear end, as shown.

My toy gun is designed primarily for use in detonating charges prepared expressly therefor and in firing projectiles from the barrel 7 by means of said charges. When used for this purpose, the mode of operation is as follows: The explosive charge, which consists of a small cylinder of a suitable explosive mixture—such as sulfur, chlorate of potash, sand, and some agglutinant (charges of the desired form being shown in Fig. 6)—is seated in the rear end of the touch-hole 8, with its forward end resting against the shoulder 10, formed in the touch-hole, and its rear end projecting out beyond the end of the barrel 7. The projectile, if any is to be used, is then inserted into the barrel 7 and the plunger 21 is drawn back against the tension of the elastic cord 26 until the notch 27 engages with the catch of the trigger. When the trigger is released, the plunger is drawn forward through the action of the elastic cord, the metallic cap 23 strikes against the explosive charge, detonating it, and causing the discharge of the projectile from the barrel.

Projectiles of any character adapted to fit the barrel 7 may be discharged in this way; but a preferred form of projectile consists of a cylinder composed of any of the well-known mixtures adapted to ignite readily and practically inextinguishable after once having been ignited. Another projectile especially suitable for use in a gun of this kind is a small whistling-bomb of the kind well known to manufacturers of pyrotechnics. When either form of projectile is employed, it is ignited by means of the explosion of the charge in the touch-hole, and when it emerges from the barrel 7 it is a flaming mass, which continues to burn throughout its entire flight.

When the gun is to be used to discharge projectiles without the aid of an explosive charge, the latch 18 is withdrawn from the holes 19 and 20 and the frame 14 either turned backward to bring the barrel 7 in contact with the rear portion of the stock or separated from the gun by withdrawing the ends of the frame from the openings 15. When the barrel is out of the way, the plunger 21 may be used to drive projectiles of any suitable form from the gun by impact.

It will be observed that the upper surface of the extension 2 is grooved, so as to form

guideways for the reciprocations of the plunger 21 and also to direct the movement of a projectile driven forward by the impact of the plunger. The operation of the plunger 21 when the gun is used to propel projectiles by impact differs slightly from guns of this same general type, as will presently appear. Owing to the way in which the rear end of the slot 5 is formed and the point at which the plunger 21 is secured to the elastic cord 26, the plunger 21 receives when released from the trigger 3 a forward impulse from both ends of the elastic cord 26. This combined impulse does not continue throughout the entire forward movement of the plunger, but ceases after the plunger has moved forward a short distance and acquired some velocity. During the rest of its forward movement the plunger is impelled by the forward portion of the cord only, and as it nears the forward end of its movement it is retarded by the rearward portion of the cord, which causes the plunger to travel backward a short distance after reaching the forward limit of its movement. This peculiar movement of the plunger 21 is of special utility in connection with the barrel 7 when explosive charges are used in the gun. By providing for a recoil of the plunger after it strikes a charge the barrel has the touch-hole therein fully exposed, so that another charge may be readily inserted in the touch-hole. Without provision for a recoil after the detonation of the charge the plunger would lie in contact with the touch-hole, and it would be necessary to force the plunger back before a charge could be inserted. A further disadvantage which would result would be the liability to frequent accidental discharges from the slipping of the plunger while the charge was being inserted. Such accidental discharges are not only apt to burn the fingers of the person using the gun, but more serious injuries might easily result.

Having now fully described the construction and operation of my toy gun, what I claim as new, and desire to secure by Letters Patent, is—

1. The combination in a toy gun, of a support slotted longitudinally for a portion of its length, a plunger adapted to reciprocate on said support, an elastic cord having its ends secured on the under surface of the support beyond the ends of the slot and having its middle portion drawn upward through the slot and secured to the under surface of the plunger, substantially as described.

2. A toy gun having a barrel provided with a touch-hole communicating with the bore of the barrel, an annular shoulder formed in the touch-hole near its outer end and adapted to form a seat for a block of explosive, substantially as described.

3. The combination in a toy gun, of a stock, a forward extension therefrom forming a support, a frame pivotally connected at its rear end to the stock, a barrel adapted to rest on

the support and pivotally mounted on said frame, and a latch whereby the barrel is held in position on the support, substantially as described.

4. The combination in a toy gun, of a stock, an extension therefrom forming a support and provided with a longitudinal slot, a barrel having lugs adapted to engage said slot, a frame pivotally connected at its rear end to the stock and at its forward end to the barrel,

and a latch adapted to hold the lugs on the barrel in engagement with the slot, substantially as described.

In testimony that I claim the foregoing as my own I have hereto affixed my signature in ¹⁵ the presence of two witnesses.

ANTONIO DELGRANDE.
